Attorney

UNITED STATES PATENT OFFICE

ROSS F. GEORGE, OF SEATTLE, WASHINGTON

RESERVOIR ATTACHMENT FOR PENS

Application filed September 28, 1926. Serial No. 138,165.

My invention relates to a pen and to a reservoir attachment therefor, and particularly to a construction wherein an underfeeder and an overfeeder combine to form a main ink reservoir, located both above and below the pen body, as held in its writing position, and cooperate further with each other and the pen to thin down the ink body as it approaches the writing tip, in whatever position the pen may be held or flexed while in use, and to feed the ink thus in condition for use to the writing tip of the pen over the upper side of the pen body, in this manner insuring against the formation of a blot by reason of the ink hanging from the under side of the pen and yet obtaining a large volume in the reservoir to the end that frequent dipping may be obviated.

Underfeeders and overfeeders alone are commonly associated with pens, and they have frequently been associated together. By reason, in some cases, of their inflexibility, and in other cases, of their arrangement relative to each other and to the pen, they have not generally been found satisfactory in combination, though the increased capacity thus obtained is highly desirable. It must be borne in mind that to permit an underfeeder to deliver ink direct to the writing tip of the pen is almost certain to cause a blot, for unless the ink is fed to the writing tip along the upper side of the pen, it is almost sure to hang and bleed from the underfeeder, and to cause too great an excess of ink, and this is particularly noticeable at the end of a line. In order to feed the ink properly over the upper side of the pen and to insure its withdrawal from the writing tip at the end of a stroke, an overfeeder must be employed with an underfeeder. Further, the two feeders, but more especially the underfeeder, must thin down the ink body contained within it and between itself and the pen so that it may pass by capillary attraction through the slit between nibs of the pen and so that it will not bleed or drip by reason of its collective weight from the lower end of the feeder. My present invention, therefore, relates especially to a combination between an overfeeder and an underfeeder, associated with a flex-

ible pen, to properly feed the ink to the writing tip of the pen, and to withdraw it therefrom as the flexure on the pen is relieved.

Those features comprising my invention, and which are illustrated in the accompanying drawings will be described hereinafter and particularly defined by the claims terminating this specification.

Figure 1 is a perspective view showing the form of construction of the feeder.

Figure 2 is a longitudinal section therethrough along a slit between nibs.

Figure 3 is a section on line 3—3 of Figure 2.

It will be observed that in the form of the pen shown, an overfeeder, generally designated by the numeral 1, is located on the upper or convex side of the pen, and extends from a point well up on the pen body towards and substantially to the writing tip, over which it preferably extends. This extension is indicated generally by the numeral 10. An underfeeder, generally designated by the numeral 2, lies at the lower or concave side of the pen body, and extends from a point substantially the same as the overfeeder 1, or at least well above the writing tip, towards the writing tip but stopping short thereof. The lower end 20 of the underfeeder, as illustrated, stops back of the tip 10 of the overfeeder and back of the tip 30 of the pen 3.

It will be noted in Figure 2 that the underfeeder 2, at its tip, approaches and lies closely adjacent, the underside of the pen, generally touching the pen, although this is not essential. The purpose of this is to thin down the body of ink towards the tip of the feeder so that it will pass readily by capillary attraction through the slit or slits 31 between the nibs but will not be enabled to collect in so heavy a drop that it will bleed or drip from the tip of the underfeeder. The same is true of the overfeeder, and while it is desirable, in connection therewith, it is quite essential with respect to the underfeeder.

It may be pointed out here that the feeders 1 and 2 may be fixed in position relative to the pen in any suitable manner, as shown herein, but preferably by a flexible mount-

ing. For example, a band 11 at the upper end of the overfeeder encircles the pen 3 partially or wholly, and is connected to the feeder 1 by a flexible neck 13. As shown in Figure 2, it may engage and grip a similar band 21, connected to the underfeeder 2 by a flexible neck 23. This form is designed for use where extreme flexibility in the support for the feeders is desired, and where it is intended that the pen should project but slightly from its holder. The flexible necks 13 and 23 are doubled under so that the bands 11 and 21 lie beneath the respective feeders.

In Figure 1, the overfeeder 1 has been shown as centrally divided by a longitudinally extending depression 12, which may be formed with relatively steep side walls whereby two ink wells 14 are provided at each side of the depression 12, and between the feeder and the back of the pen 3, and the channel 12, if properly formed for the purpose, may receive and retain ink as well. The chief function of the depression 12, however, is to divide the reservoir into semi-independent ink wells. The edges of the reservoir, as indicated at 15, (see Fig. 3), are spaced somewhat above the pen body so that a brush or blotter may be inserted readily for cleaning.

30 Due to the flexing of the pen in writing, and to the flexibility of the overfeeder 1, as a whole, on its neck 13, a local reservoir is formed between the tip 10 of the overfeeder and the upper side of the writing tip 30 of the pen. This local reservoir communicates with the writing tip 30 through the slits 31, or equivalent means, and is in communication with the main reservoir 14 through the channel provided between the lower end of the feeder 1 and the pen, and along which the ink is drawn by capillary attraction toward the pen tip.

The underfeeder 2 is formed generally somewhat flat, having side flanges 24 forming generally to a plane surface parallel to the writing sheet, but spaced therefrom. It also has inwardly directed flanges 25 providing a longitudinal slit 26 down its center. By these means, the pen can be filled by dipping and there are provided channels which are open and accessible for the insertion of a brush or blotter to clean the reservoir 27, between the feeder 2 and the under side of the pen. The inwardly directed flanges 25 serve the further purpose of dividing the reservoir 27 in the same manner that the depression 12 separates the reservoir 14. The tip of the underfeeder is so placed relative to the pen, that the ink is thinned out to a fine film, so that it readily will pass through the slits 31 between nibs, to reach the upper reservoir.

65 The depression 12 is accentuated to the point that a slit 17 is formed between two separated flanges 18. By this means free ac-

cess is had to the interior of the upper reservoir for filling and cleaning, and the slot 17 acts as a breather. The tip 30 of the pen illustrated in Figure 2 is not bent, although the tip 10 of the overfeeder 1 may be slightly turned up. This, in effect, forms a local reservoir at 33, between the upturned tip 10 and the tip 30 of the pen. The manner of supporting the feeders, with the bent-under bands 11 and 21 illustrated, has been previously described. It should not be understood, however, that there is any essential connection between this particular type of feeder and this support; rather, the feeder may be employed with any proper support and the support with any feeder.

What I claim as my invention is:

1. In combination with a pen, a feeder attachment therefor extending longitudinally of and generally spaced from the pen, and lying closely against the pen at its tip, and means disposed beneath the upper end of the feeder and engageable with the pen body to secure the feeder thereon.

2. In combination with a pen, a feeder attachment therefor generally spaced from and extending longitudinally of the pen, feeder securing means engageable with the pen body, and a connection between the feeder and that edge of the feeder securing means which is farthest from the pen tip.

3. In combination with a pen, a feeder attachment therefor generally spaced from and extending longitudinally of the pen, and a bent-under neck at the upper end of the feeder terminating in a feeder securing means adapted for securement to the pen body.

4. In combination with a pen having a flexible writing tip, a feeder attachment therefor comprising a band adapted for securement to the pen body, a flexible neck extending from the edge of the band farthest from the pen tip, and a feeder body bent back over the band and extending to the pen tip.

Signed at Seattle, Washington, this 20th day of September, 1926.

ROSS F. GEORGE.
